UNITED STATES PATENT OFFICE.

PETER MUZYCZKA, OF BRONX, NEW YORK.

SAND DISTRIBUTOR.

Application filed June 27, 1924. Serial No. 722,686.

To all whom it may concern:

Be it known that I, PETER MUZYCZKA, a citizen of Poland, residing at Bronx, in the county of Bronx and State of New York, have invented certain new and useful Improvements in Sand Distributors, of which the following is a specification.

This invention relates generally to a sand applying apparatus for use on cars or trains, the invention having more particular reference to the control means for the discharge opening from the sandbox, and having for its object the provision of a novel and improved type of control device.

For further comprehension of the invention, and of the objects and advantages thereof, reference will be had to the following description and accompanying drawing, and to the appended claims in which the various novel features of the invention are more particularly set forth.

Fig. 1 of the drawing is a side view of my improved device, indicating part of the car in dot and dash lines.

Fig. 2 is an enlarged transverse vertical sectional view taken generally along the line 2—2 of Fig. 1.

Fig. 3 is an enlarged horizontal sectional view taken on the line 3—3 of Fig. 1.

Fig. 4 is a longitudinal vertical sectional view taken on the line 4—4 of Fig. 3.

Fig. 5 is a fragmentary longitudinal vertical sectional view showing a modification.

In the drawing the reference numeral 10 indicates a portion of the platform of an electric or other car, and 11 the sandbox located under the platform and which may be arranged for filling in any suitable manner. Fixed as by the nuts 15 to the underside of the platform 10, and depending therefrom are the vertical rods 16 which form crosshead guides for a crosshead 17 consisting of the upper and lower horizontal bars which are rigidly united by the tubular members 18' which freely encircle the rods 16. Fixed to this crosshead 17 midway between the rods 16 is a thrust rod 18 which extends upward through a suitable opening in the platform 10 and has a foot pedal 19 on its upper end. Projecting from

the lower side of the crosshead 17 midway between the rods 15 are the lugs 21 to which is hinged the upper end of a link 22 which extends downwardly and rearwardly and is connected at its other end to the forward end of the rigid stem 23 of a valve plate 24 which controls the discharge of sand from the box 11. The valve plate projects into one end of the box and is accommodated between the bottom 11' of the box and a supplementary bottom member 11^a which is spaced above the main bottom just sufficient distance to accommodate the valve plate. The parts 11' and 11^a are formed with discharge openings 26 and 27 while the plate 24 is formed with an opening or port 28 which is normally held out of registry with the openings 26 and 27 by means of a pair of tension springs 30 which connect at one end to the platform 10 and at opposite ends to the crosshead 17. A rubber hose 31 leads downward from the bottom of the box 11 to conduct the sand to a point in front of the wheel of the car.

To guide the valve stem 23 it has fixed to the forward end thereof the crosspiece 35 which engages in the channeled guide elements 36 which extend horizontally between the lower ends of the rods 16 and the box 11. The crosspiece 35 may have anti-friction rollers 37 on its ends. As will be apparent, when the pedal 19 is depressed by the motorman of the car the vertical movement of the thrust rod 18 will be transferred by the link 22 to a horizontal movement of the valve stem 23 and the valve 24, bringing the latter into position with its port 28 in registry with the discharge openings in the bottom members of the sandbox, the springs 30 returning the parts to normal position when the pedal is released. A curved yoke 38 may connect the forward ends of the guide 36 and limit movement of the link 22. These parts may be enclosed in and protected by a suitable housing fixed to the underside of the car platform.

In Fig. 5 I have shown a modified construction arranged to agitate the sand in the box slightly when the pedal is depressed. As here shown the rod 16' cor-

responding to the rod 16 does not extend at its upper end through the platform 10 but into a guide element 40 under the latter. Upon this rod 16' is fixed a stepped member 41 which is adapted to be engaged by the end of a lever arm 42 fulcrumed under the platform 10 by means of a slot and pin connection 43. This lever arm is adapted to be engaged and depressed by a thrust rod 44 10 slidable in a bearing element 45 and extending upward through the platform and having a pedal 46 on its upper end, a coiled tension spring 47 being connected at one end to the arm 42 and at its other end to the 15 platform and urging the arm upward and forward. With this arrangement the false bottom 11^a in the sandbox is dispensed with and a suitable pair of guide members are formed on the side of the box for the 20 valve plate which latter is formed with a number of upwardly projecting tongues or spikes spaced thereover. The parts are otherwise as previously described. When the pedal 46 is depressed the arm 42 engages 25 successively the various steps on the member 41 as it swings downward, there being a slight backward movement of the rod 16' when the arm is riding from one step to the other with a consequent movement of 30 the valve and agitation of the sand in the box 11. In this arrangement I have indicated the connection between the valve stem 23 and crosshead 17 as being effected by a bell crank lever 50.

35 While I have illustrated and described a preferred embodiment of my invention it is to be understood that I do not limit myself to the precise construction herein shown, and that various changes and modifications 40 might be made therein without departing from the spirit and scope of the invention as defined in the appended claims.

Having thus described my invention what I claim as new and desire to protect by 45 Letters Patent of the United States is as follows:—

1. In a device of the class described, a sandbox having a discharge mouth, a horizontally movable plate valve controlling said mouth, a pair of fixed vertical rods, a crosshead guided on said rods, a pedal attached to said crosshead, and an operative connection between said crosshead and said valve.
2. In a device of the class described, a car 50 platform, a crosshead guide depending therefrom, a crosshead slidable on said guide, and provided with an upwardly extending rod adapted for operation by a foot pedal, a sandbox mounted under the car platform, and provided with a discharge mouth in its lower end a horizontally movable valve plate controlling said mouth, a stem connected to said valve plate, and operative connections between said crosshead and said stem whereby vertical movement of 55

the former imparts horizontal movement of the latter.

3. In a device of the class described, a car platform, a crosshead guide depending therefrom, a crosshead slidable on said guide, and provided with an upwardly extending rod adapted for operation by a foot pedal, a sandbox mounted under the car platform, and provided with a discharge mouth in its lower end a horizontally movable valve plate controlling said mouth, a stem connected to said valve plate, and operative connections between said crosshead and said stem whereby vertical movement of the former imparts horizontal movement of the latter, comprising a link extending obliquely downward from said crosshead to said stem.

4. In a device of the class described, a car platform, a crosshead guide depending therefrom, a crosshead slidable on said guide, and provided with an upwardly extending rod adapted for operation by a foot pedal, a sandbox mounted under the car platform, and provided with a discharge mouth in its lower end a horizontally movable valve plate controlling said mouth, a stem connected to said valve plate, and operative connections between said crosshead and said stem whereby vertical movement of the former imparts horizontal movement of the latter, comprising a link extending obliquely downward from said crosshead to said stem, a pair of guide elements parallel to said stem, and a crosspiece projecting from the said stem and engaging at its ends in said guide elements.

5. In a device of the class described, a car platform, a crosshead guide depending therefrom, a crosshead slidable on said guide, and provided with an upwardly extending rod adapted for operation by a foot pedal, a sandbox mounted under the car platform, and provided with a discharge mouth in its lower end, a horizontally movable valve plate controlling said mouth, a stem connected to said valve plate, and operative connections between said crosshead and said stem whereby vertical movement of the former imparts horizontal movement of the latter, comprising a link extending obliquely downward from said crosshead to said stem, and springs connected to said crosshead for moving the same upward.

6. In a device of the class described, a car platform, a crosshead guide depending therefrom, a crosshead slidable on said guide, and provided with an upwardly extending rod adapted for operation by a foot pedal, a sandbox mounted under the car platform, and provided with a discharge mouth in its lower end, a horizontally movable valve plate controlling said mouth, a stem connected to said valve plate, and operative connections between said crosshead and said stem.

stem whereby vertical movement of the former imparts horizontal movement of the latter, a stepped member projecting outward from said rod, a lever arm connected at one end to the platform by a slot and pin connection and engaging the said member at its opposite end to depress the

latter, a thrust rod bearing downward on said lever arm, and a pedal on the upper end of said thrust rod.

In testimony whereof I have affixed my signature.

PETER MUZYCZKA.
